DESIGN.

E. C. BRIGGS.

PENNANT.

APPLICATION FILED OCT. 8, 1917.

57,583.

Patented Apr. 26, 1921.

Elinor C. Briggs, Inventor,
By Frank A. Lehman Attorney

UNITED STATES PATENT OFFICE.

ELINOR C. BRIGGS, OF PAWHUSKA, OKLAHOMA.

DESIGN FOR A PENNANT.

57,583.

Specification for Design. Patented Apr. 26, 1921.

Application filed October 8, 1917. Serial No. 195,464. Term of patent 3½ years.

To all whom it may concern:

Be it known that I, ELINOR C. BRIGGS, a citizen of the United States of America, and resident of Pawhuska, in the county of Osage and State of Oklahoma, have invented a new, original, and ornamental Design for a Pennant, of which the following is a specification, reference being had to

the accompanying drawing, forming part thereof.

The figure is a plan view of the pennant showing my new design.

I claim:

The ornamental design for a pennant, as shown.

ELINOR C. BRIGGS.
